UNITED STATES PATENT OFFICE.

HENRY DE SMITH, OF ROCHESTER, NEW YORK, ASSIGNOR TO M. D. KNOWLTON COMPANY,
OF ROCHESTER, NEW YORK, A CORPORATION OF NEW YORK.

HUMIDIFIER.

No. 864,084.

Specification of Letters Patent.

Patented Aug. 20, 1907.

Application filed November 23, 1906. Serial No. 344,780.

To all whom it may concern:

Be it known that I, HENRY DE SMITH, a citizen of the United States, and a resident of Rochester, in the county of Monroe and State of New York, have invented certain new and useful Improvements 5 in Humidifiers, of which the following is a specification.

My invention relates to humidifiers and has more special reference to a humidifier adapted for use in 10 moistening so-called "stay material" used in the manufacture of paper boxes. This stay material is usually formed of tough fibrous paper adhesively coated or gummed on one side thereof which, for certain commercial uses, is cut into long strips and 15 put up in the form of rolls. In the subsequent use of this stay material it is necessary that it be sufficiently pliable to readily conform to any shape to which it may be subjected in the operation of applying the same to a box. Such material, however, is 20 obviously very susceptible to atmospheric conditions and, in the event of being left for any considerable time in a warm or dry place, as it is liable to be in factories, it dries out very quickly and, by reason of its adhesive coating, becomes more or less brittle 25 and loses that degree of pliability desirable for its most efficient use.

Another undesirable feature resulting from the undue drying out of the stay material is this: When such stay material is used on box-corner staying 30 machines it is usually placed on a reel from which it is fed by suitable feeding mechanism to a position between co-acting clamping dies which operate to press the stay material upon the corners of an interposed box. During the passage of the stay material 35 from the reel to the clamping dies, it is fed over a dampening roller for the purpose of having its gummed surface dampened and rendered adhesive. When, however, the stay strip has become unduly dried out, the moisture received on its gummed surface 40 from said dampening roll is quickly absorbed by the paper and the gum or adhesive thereby prevented from retaining sufficient moisture to maintain its most effective adhesive qualities.

Because of the aforesaid objectionable features resulting from the undue drying out of rolls of stay 45 material of the character referred to, it has been the main object of my present invention to provide a cheap and simple humidifier adapted for effectively moistening or maintaining moist such rolls 50 of stay material.

To this end the invention consists in the novel features of construction and combinations of parts hereinabove set forth in detail and pointed out in the appended claims.

Referring now to the accompanying drawings forming part of this specification: Figure 1 is a sectional elevation of a humidifier embodying my invention, having a number of rolls of stay material contained therein. Fig. 2 is a horizontal section on line 2—2 of Fig. 1. Fig. 3 is a bottom view of a roll supporting device forming part of the humidifier; and Figs. 4 and 5 are detail views of parts of the humidifier to be hereinafter referred to.

Similar reference characters designate like parts in the several figures of the drawings.

The humidifier in the form shown in the drawings comprises a somewhat elongated cylindrical-shaped receptacle 1 having at its upper end a removable cover 2 and having at its lower end within the same a reservoir for containing the moisture-producing 70 water, which reservoir may be provided by utilizing the bottom of the receptacle itself but which preferably and as shown in the drawings is provided by a pan 3 removably seated at the bottom of said receptacle.

As a means for supporting the rolls of stay material (indicated at s) within the receptacle 1, I have provided a device comprising a supporting base 4 having a central vertically-arranged spindle 5, the said device as a whole being removably located within the receptacle 80 1 and adapted to rest within the pan 3. In placing a roll of stay material upon this device, the roll is slipped over the upper end of the spindle by entering the latter through the usual central opening in the roll, and then, in the event of such roll being the first or only 85 one to be placed on the device it will drop down upon the base 4. Preferably, and as shown in the drawing, the said base is made in the form of a spider comprising a central hub 6 having radially extending arms 7. This open or spider form of supporting base provides 90 for the practically unobstructed exposure of the supported roll to the moisture arising from the reservoir 3.

As it is usually desired to place a considerable number of rolls of stay material in the humidifier, and as it is desirable that such rolls be held in spaced relation 95 to each other in order to permit of the ready access of the moisture to practically the entire exterior surface of the rolls, I have provided roll spacing means in the form of spiders similar to the spindle base, the same comprising a hollow central hub 8 having radially extending arms 9. These spacing spiders are adapted to be slipped over the spindle 5 for location between the successive rolls s, as shown in Fig. 1, and, by reason of their open spider form, maintain the rolls in sufficiently open spaced relation to each other as to expose 100 practically their entire exterior surface to the moisture within the humidifier.

As a further means for assuring a more ready and com-

plete contact of the moisture with the rolls, I have made the spindle 5 hollow to permit of the circulation therethrough of the moisture and provided the same with perforations 10 through which the moisture may 5 find exit for contact with the inner or adjacent portions of the rolls.

The operation of placing the rolls of stay material upon the holder 4-5, or removing the same therefrom, may be effected with the holder in position within the 10 receptacle 1, but it is more conveniently effected outside of said receptacle, and this is permitted by the ready removability of the holder from the receptacle.

The reservoir at the bottom of the receptacle 1 may also be filled or replenished in any suitable or desired 15 manner, but as a simple and convenient means for accomplishing such object, I have provided the receptacle 1 with an opening in one side thereof adjacent to its lower end and provided the pan 3 with an extension 3' for extending through said opening into convenient position to have water poured thereinto from the exterior of the receptacle. This permits of the filling or replenishing of the pan 3 without the necessity of removing the same from the receptacle and also without the necessity of removing or otherwise disturbing 20 the rolls of stay material contained in the receptacle.

I have herein described the humidifier embodying my invention as being specially adapted for use in moistening, or maintaining moist, rolls of stay material. It will be obvious, however, that the said humidifier 30 may be employed for moistening articles other than rolls of stay material and I therefore intend the invention to be considered accordingly.

What I claim is:

1. A humidifier comprising a receptacle having therein a liquid-containing reservoir, an article-holding spindle, and article-spacing means.
2. A humidifier comprising a receptacle having therein a liquid-containing reservoir, an article-holding spindle, and article-spacing means surrounding said spindle.

3. A humidifier comprising a receptacle having therein 40 a liquid-containing reservoir, an article-holding spindle, and article-spacing means in the form of radial-armed hubs loosely fitting over the said spindle.

4. A humidifier comprising a receptacle having therein 45 a liquid-containing reservoir, and a hollow perforated article-holding spindle.

5. A humidifier comprising a receptacle having therein a liquid-containing reservoir, a hollow perforated article-holding spindle, and article-spacing means in the form of radial-armed hubs loosely fitting over the said spindle. 50

6. A humidifier comprising a receptacle having therein a liquid-containing reservoir, a centrally located hollow perforated spindle adapted to loosely receive thereover rolls of stay material, and radial-armed hubs loosely fitting over the said spindle for location between the rolls 55 of stay material thereon.

7. A humidifier comprising a receptacle having therein a liquid-containing reservoir, and a hollow perforated article-holding spindle supported with one end adjacent to said reservoir. 60

8. A humidifier comprising a receptacle having therein a liquid-containing reservoir, and a hollow perforated article-holding spindle mounted on a base supported in said reservoir.

9. A humidifier comprising a receptacle having therein 65 a liquid-containing reservoir, and a hollow perforated article-holding spindle mounted on a radial-armed base.

10. A humidifier comprising a receptacle having an opening in one wall thereof, and a liquid-containing reservoir 70 removably located within said receptacle and having an extension thereof projecting through said opening in the receptacle wall.

11. A humidifier comprising a receptacle having an opening in one wall thereof, a liquid-containing reservoir removably located within said receptacle and having an 75 extension thereof projecting through said opening in the receptacle wall, and an article-holding spindle supported above said reservoir.

Signed at Rochester, in the county of Monroe and State of New York this 9th day of November, A. D. 1906.

HENRY DE SMITH.
